The ornamental design for an ink cartridge for printer, as shown and described.

DESCRIPTION

FIG. 1 is a front, bottom and left side perspective view of an ink cartridge for printer;

FIG. 2 is a rear, bottom and left side perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a left side view thereof; and,

FIG. 8 is a right side view thereof.
